US00D711883S

(12) **United States Design Patent**
Brunner et al.

(10) **Patent No.:** **US D711,883 S**
(45) **Date of Patent:** **** Aug. 26, 2014**

(54) **SCANNER**

(71) Applicants: **Alexander Brunner**, Howell, MI (US);
Sidney Trey Smith, Howell, MI (US);
Randall Timothy Long, Brighton, MI (US)

(72) Inventors: **Alexander Brunner**, Howell, MI (US);
Sidney Trey Smith, Howell, MI (US);
Randall Timothy Long, Brighton, MI (US)

(73) Assignee: **Meditory LLC**, Brighton, MI (US)

(**) Term: **14 Years**

(21) Appl. No.: **29/449,805**

(22) Filed: **Mar. 15, 2013**

(51) LOC (10) Cl. **14-02**

(52) U.S. Cl.

USPC **D14/420**

(58) **Field of Classification Search**

USPC D14/420-423, 385; 433/222.1, 223, 433/213-215, 73, 24, 29, 37, 202.1; 700/98, 97, 118, 161, 163, 182; 264/16, 17, 19, 219, 225; 374/1; 707/104.1; 249/54; 600/590; D20/1-9; 194/205, 206, 244, 321, 345, 346, 350; D18/3.3, 4.4, 12, 49; D99/28, 43; 235/381

See application file for complete search history.

(57) **CLAIM**

We claim the ornamental design for a scanner, as shown and described.

DESCRIPTION

FIG. 1 is a perspective view of a scanner showing the new design;

FIG. 2 is a front elevation view, the rear view being a mirror image thereof;

FIG. 3 is a top plan view thereof;

FIG. 4 is a bottom view thereof;

FIG. 5 is a left side view; and,

FIG. 6 is a right side view.

1 Claim, 6 Drawing Sheets
